UNITED STATES PATENT OFFICE.

WALTER STRANDERS, OF NEW YORK, N. Y., ASSIGNOR TO CHARLES C. SHEPHERD, OF PASSAIC, NEW JERSEY.

DISSECTED TOY PICTURE.

SPECIFICATION forming part of Letters Patent No. 242,709, dated June 7, 1881.

Application filed April 20, 1881. (No model.)

To all whom it may concern:

Be it known that I, WALTER STRANDERS, of the city and State of New York, have invented an Improvement in Dissected Toy Pictures, of which the following is a specification.

Toy pictures and maps have been made in a number of ways, the object being to amuse and instruct young persons while placing the pieces together.

10 The present invention relates to a dissected picture in which provision is made for building up one thought or expression after another by the addition of other pieces to take the place of pieces that are introduced in the foundation design of the toy.

15 I have illustrated the present invention in connection with the well-known jingle called "The house that Jack built."

20 In the drawings, Figure 1 represents simply the house that Jack built, with the surrounding shrubbery, &c. This picture is placed upon a backing of wood, card-board, or other suitable material, and divided up into sections, which are numbered 1, 2, 3, &c. There may 25 be more divisions than those, if desired. The other figures show the sections that are to be used successively to replace the correspondingly-numbered sections in Fig. 1. For instance, remove section No. 1 from Fig. 1 and 30 replace it by section No. 1 from Fig. 2, and you have "This is the malt that lay in the house that Jack built." Then remove section No. 2 from Fig. 1 and replace it by section No. 2 from

Fig. 2, and you have "This is the rat that ate the malt that lay in the house that Jack 35 built." Then substitute section No. 3, Fig. 2, for the corresponding section in Fig. 1, and you have "This is the cat that killed the rat that ate the malt that lay in the house that Jack 40 built," and so on, by introducing into Fig. 1 45 the successive sections shown in Fig. 2, the picture No. 1 will be complete after each substitution, and the incidents or statements of the jingle will be illustrated in the Fig. 1.

It will be evident that this character of toy 45 picture can be made to represent various devices—such, for instance, as cages for animals, with sections that can be removed and others representing animals be introduced; and many 50 other kinds of dissected pictures can be made in which one or more sections can be removed and other sections introduced to represent additional devices, articles, or ideas.

I claim as my invention—

The combination, with a dissected toy picture, of one or more substitute sections to be introduced into the said toy picture to convey something additional to the original dissected toy picture, substantially as set forth.

Signed by me this 7th day of April, A. D. 60 1881.

WALTER STRANDERS.
